METHOD FOR THE REPAIR AND CONDITIONING OF NYLON FABRIC

Harry McAdams, Philadelphia, Pa.

Application June 16, 1948, Serial No. 33,355

7 Claims. (Cl. 66—1)

1

This invention relates to improvements in process for the conditioning of knitted nylon fabrics.

The primary object of this invention is the provision of an improved process for the repair of fabric manufactured of knitted synthetic linear condensation polyamide yarn for the purpose of stitch setting the fabric in the zone of repair so the appearance of the repaired area will not readily disclose the fact that the article has been repaired.

It is well known in the knitting art that during the knitting of fabric and such other operations as dyeing and finishing "pull yarns" occur, and sometimes yarns are frayed and broken. Ordinarily this eliminates the fabric or article from consideration as a salable "first," and depending upon the degree of perfection, in repair, the article or fabric can be commercially disposed of as an "irregular" "second," "third," etc. With the improved process and apparatus of the present invention it is now possible to condition the fabric in the repaired section, especially if made of nylon, so as to set the stitches after the repair operation under circumstances which will greatly improve the appearance of the area or zone of repair. Thus in the case of fabric where the question is merely that of straightening out "pull threads" the article can be conditioned to the extent that it is commercially salable as a "first."

It is well known in the art relating to the finishing of hosiery that stockings fabricated of synthetic linear condensation polyamide fibres require a setting of the crimp or stitch loop, and when so set the stitch will always resume the set position unless the stocking is subjected to treatment at a greater temperature than the stitch setting operation. However, it is present conventional practice after finishing of the stocking, to repair pull threads and other areas where repair is necessary. This operation consists of rearranging the crimp, loops and stitches to conform as nearly as possible to natural appearance. However, the repaired zone, even where the repair only concerns "pull threads" can be readily detected, even by those unskilled in the art of inspection and, of course, this decreases the value of the product.

With the improved process of the present invention it is now possible to economically repair nylon fabric so that after the straightening operation the stitch or yarns can be set again in normal condition, so as to eliminate detection of repair in the area being treated, particularly where the repair consists in straightening out of "pull threads."

Other objects and advantages of the invention will be apparent from the following detailed description.

In the accompanying drawing, forming a part

2

of this specification and wherein similar reference characters designate corresponding parts throughout the several views,

Figure 1 is a fragmentary view showing apparatus used in connection with the repair process of nylon fabric.

Figure 2 is an enlarged cross sectional view taken substantially on the line 2—2 of Figure 1.

Figure 3 is a perspective view showing how an operator stretches the fabric over the apparatus for the purpose of repair treatment.

Figure 4 is a cross sectional view taken thru a steam control valve embodied as a part of the apparatus.

In the drawing, wherein for the purpose of illustration is shown only a preferred embodiment of the invention, the letter A may generally designate the apparatus. It may be mounted upon a suitable framework B. The latter may include a table top 10 and a supporting structure 11.

The principal part of the repair apparatus A consists of supporting receptacle 15, formed of aluminum, plastic or the like. It may be referred to as "cup-shaped" and includes the upper conical-shaped portion 20 having a compartment 21 therein which flares upwardly with an increasing width to a mouth which terminates at the top margin or edging 22, over which the fabric is stretched. The receptacle 15 includes a hollow base 25 connected by a reduced neck 26 with the upper portion 20. The lower margin of the base 25 is outwardly flanged at 27 to permit the same to rest upon the top surface of the table 10. A passageway 30 extends thru the connecting portion 26 and opens into the compartment 21 and thru which saturated live steam is discharged. It will be noted that the receptacle is of a length which will enable it to be conveniently held in the hand of an operator with the stocking draped over the mouth of the receptacle so that the repair zone can be rendered taut (see Figure 3).

The apparatus A further includes a vertical length of pipe 40 securely fixed at 41 in the table top 10 and projecting thereabove, where the same is provided with a fixed nipple 42, adapted to detachably fit in the passageway 30, and thru which nipple the saturated live steam is discharged into the repair receptacle chamber 21.

The steam pipe 40 extends at 50 beneath the table top and has a vertical section 51 connected as at 52 to the supporting structure 11 of the framework B. In the section 51 a valve structure 53 is connected, having a body portion provided with a passageway 54 within which operates the valve body 55. The latter has connected therewith an operating handle 56 which at one end has associated therewith a bracket structure 57 to limit the closed and open positions of the valve. A spring 58 normally holds the valve body 55 into the passageway closing position shown in

Figure 4. The handle 56 has an end 60 which is positioned so that the operator may conveniently press a leg or foot thereagainst for the purpose of opening the valve and permitting a puff or puffs of saturated live steam to pass thru the pipe line into the repair receptacle and over the fabric which is stretched tautly across the edge 22.

Referring to the method or process of conditioning knitted nylon fabric, as before mentioned, it is known that knitted fabric constructed of synthetic linear condensation polyamide yarn requires a setting operation in order to permanently set the crimp. To that end the operator will take the nylon fabric article, designated at D in Figure 3 of the drawing, and slip it over the mouth end of the receptacle 15 stretching the area or zone to be repaired over the mouth of the compartment 21, as shown in Figure 3. The fabric is so stretched or tightened at the damaged area over the mouth so that the stitches or loops are all brought approximately to the same normal size. The operator is then enabled to rearrange the pull yarn or the yarn to be repaired thru manipulation of stitch loops in the courses and wale lines. When the stitch and sinker loops have been rearranged to normal condition, and while the fabric is still taut, the operator then presses against the handle 56 and opening the valve to permit discharge of saturated live steam into the receptacle compartment 21 and across the tightened area of the stocking. Since the nylon stocking has already been subjected to a pre-setting operation in advance of finishing it is merely necessary to subject the zone of repair to one or more puffs of the saturated live steam for resetting the stitch loops to a natural condition. The temperature of the saturated live steam ranges between 212° F. and 240° F. The optimum temperature is preferably 224° F. and the time of subjecting the tightened zone of repair to the saturated live steam treatment may vary between a short puff or a continued steam treatment which is forced by the pressure of the steam thru the fabric over a period of time ranging from a few seconds to 1 1/4 minutes.

While the apparatus and process of this invention are particularly well adapted for the treatment of fabric constructed of nylon yarn, it can be very well appreciated that fabric constructed of yarn other than nylon, such as silk, can be similarly treated at the zones of repair.

In order to protect the operator the entire detachable receptacle 15 may be made of insulation or the same may be insulated against the transfer of the heat therethru by means of a suitable external covering.

Various changes in the steps of the process and change, size and arrangement of parts may be made to the form of invention herein shown and described without departing from the spirit of the invention or the scope of the following claims.

I claim:

1. The process for repair of articles manufactured of synthetic linear condensation polyamide yarn the steps which consist in initially rendering the article taut at the repair zone, mechani-

cally repairing and rearranging the yarn at the zone of the article to be repaired, and while so tightened subjecting the said article at the zone of repair to a saturated live steam treatment for setting the position of the yarn.

5 2. In a process for repair of articles manufactured of nylon yarn the steps which consist in stretching the yarn at the zone of repair and while in such condition rearranging the yarn into proper position, and while so stretched subjecting the article at the zone of repair to a saturated live steam treatment for setting the yarn.

10 3. In a process for repair of yarn damaged areas of knitted nylon fabric the steps which consist in stretching the damaged area and while in such stretched condition rearranging the yarns into the most desirable natural position, and while in such position subjecting the article at the zone to be repaired to a blast of saturated live steam.

20 4. In a process for repair of yarn damaged areas of knitted nylon fabric the steps which consist in stretching the damaged area and while in such stretched condition rearranging the yarns into the most desirable natural position, and while in such position subjecting the article at the zone to be repaired to a blast of saturated live steam, at a temperature ranging between 212° F. and 240° F. for a period of time sufficient to set the stitch, crimp and loops.

25 5. In a process for the repair of articles manufactured of nylon yarn the steps which consist in stretching the article at the zone of repair across the open mouth of a receptacle, repairing said zone, and then subjecting the stretched zone of repair to the action of saturated live steam passing thru said receptacle.

30 6. In a process for repair of knitted nylon stockings the steps which consist in stretching the nylon stocking at the zone to be repaired over the open mouth of a receptacle, straightening the stitch loops at the zone to be repaired into a desired arrangement, and while in its stretched condition subjecting the zone of repair to the blast action of saturated live steam passing thru said receptacle.

35 7. The method of conditioning damaged fabric which consists in stretching the fabric at the damaged zone and while so stretched rearranging the yarns into a desirable relation, and while in stretched condition subjecting the zone of repair of the fabric to the action of saturated live steam for setting the yarns in a repair position.
